HEDDLE

Filed July 22, 1931

Inventor:

John Jacob Kaufmann,
by Jas. C. Wobensmith
Attorney.

UNITED STATES PATENT OFFICE

JOHN JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA

HEDDLE

Application filed July 22, 1931. Serial No. 552,402.

My invention relates to heddles for loom harness, and it relates more particularly to that type of heddle which is so constructed and arranged that one or more of the same 5 may be mounted at any desired place in the frame, either for the purpose of replacing a broken or damaged heddle, or for increasing the number of heddles in the harness frame, without removing the heddle supporting rods 10 from the frame.

My invention contemplates the construction of heddles of the type aforesaid, in which the main portion of the heddle is made from a thin flat strip of metal or wire, having 15 improved means at the ends thereof for mounting the same on the supporting rods.

The nature and characteristic features of 20 my invention will be more readily understood from the following description, taken 25 in connection with the accompanying drawing forming part hereof, in which:

Figure 1 is an edge view of a heddle embodying the main features of my present invention, the same being shown mounted on 25 the heddle supporting rods of the harness frame;

Fig. 2 is a face view of the heddle shown in Fig. 1, the supporting rods being shown in 30 section;

Fig. 3 is a perspective view of the end portion of the heddle, showing the same mounted on the supporting rod;

Fig. 4 is a development view of one of 35 the end members of the heddle; and

Fig. 5 is a perspective view showing the end portion of the heddle in the process of 40 assembly.

It will, of course, be understood that the drawing and description herein contained 45 are illustrative merely, and that various changes and modifications may be made in the structure disclosed without departing from the spirit of my invention.

In the particular embodiment of the invention 50 which is shown in the drawing, 10 is the main or body portion of the heddle, which is made of a thin flat strip of metal or wire, and in which the warp eye 11 is formed by slitting and expanding in any preferred manner.

At each end of the heddle there is carried a member 12, for engaging the supporting rod, which member 12 is also preferably made from a thin flat strip of metal. In Fig. 4 of the drawing, the member 12 is shown in its initial form, before it is attached to the body portion of the heddle. It will be noted that the same is somewhat wider than the body portion of the heddle, and is provided with an aperture 13 through which the end of the body portion of the heddle extends. The member 12 is bent, as at 14, so that a portion thereof embraces the end of the body portion of the heddle on each face thereof, and is permanently secured thereto in any preferred manner, such for example as by spot welding, as at 15.

The member 12, when secured to the end of the body portion of the heddle, comprises two parallel legs, each of which is provided with a cut out recess 16, the opening extending to opposite edges of the two legs, so that the same provides, in effect, a slot 17, through which the supporting rod 18 extends when the heddle is mounted in the harness frame.

Contiguous to the recess 16, on each leg of the member 12, is a lip portion 19. The lip portions 19 serve to prevent the ends of the leg portions from spreading and becoming disengaged from the supporting rods 18.

The end of at least one of the leg portions is bent outwardly from the main plane thereof, as at 20, to facilitate the mounting of the heddle on the supporting rod.

When it is desired to mount the heddle at the desired place upon the supporting rods 18, the heddle is turned upon its longitudinal axis, at right angles to the position it normally occupies when mounted on the supporting rods. The member 12 at one end of the heddle is then pushed over its rod with one of the leg portions on each side thereof, to the extreme inner end of the recess 16, so that the lip portions 19 will be brought beyond the outer edge of the rod 18, after which the heddle is turned to its proper position. The end of the heddle will now be retained upon the rod by reason of the rod extending through the slot 17, the lip portion 19 insuring against disengagement by preventing the

leg portions of the member 12 from spreading when the strain is imparted to the heddle.

After one end of the heddle is thus mounted upon its supporting rod, the other end is in like manner caused to engage its supporting rod, it being noted that the heddle may be twisted sufficiently to permit this engagement.

It will be seen that there is thus provided a heddle which may be inexpensively made, which will be durable and efficient, and which may be readily mounted at any desired place on the supporting rods, either for the purpose of replacing a broken heddle or for increasing the number of heddles in the harness frame.

I claim:

1. A heddle having members at the ends thereof for mounting the heddle on the supporting rods, said members comprising leg portions disposed in separate parallel planes, each of said leg portions having a recess therein open to the side, the recess of one leg portion opening to the side opposite that to which the recess of the other leg portion opens.

2. A heddle having its body portion made of a thin flat strip of metal or wire, members permanently secured to the side faces of the body portion at the ends thereof for mounting the heddle on the supporting rods, said members comprising leg portions disposed in separate planes, each of said leg portions having a recess therein open to the side, the recess of one leg portion opening to the side opposite that to which the recess of the other leg portion opens.

3. A heddle having its body portion made of a thin flat strip of metal or wire, members permanently secured to the side faces of the body portion at the ends thereof for mounting the heddle on the supporting rods, said members comprising substantially parallel leg portions each having a recess therein open to the side, the recess of one leg portion opening to the side opposite that to which the recess of the other leg portion opens, and lip portions contiguous to said recesses adapted to overlap the sides of the supporting rod.

4. A heddle having its body portion made of a thin flat strip of metal or wire, members secured to said body portion at the ends thereof for mounting the heddle on the supporting rods, said members being made of thin flat metal and comprising leg portions disposed in separate parallel planes, each of said leg portions having a recess therein open to the side, the recess of one leg portion opening to the side opposite that to which the recess of the other leg portion opens.

5. A heddle having its body portion made of a thin flat strip of metal or wire, members secured to said body portion at the ends thereof for mounting the heddle on the supporting

rods, said members being made of thin flat metal and comprising leg portions disposed in separate parallel planes, each of said leg portions having a recess therein open to the side, the recess of one leg portion opening to the side opposite that to which the recess of the other leg portion opens, and lip portions contiguous to said recesses adapted to overlap the sides of the supporting rod.

6. A heddle having its body portion made of a thin flat strip of metal or wire, members secured to said body portion at the ends thereof for mounting the heddle on the supporting rods, each of said members being made of a single piece of thin flat metal centrally apertured and bent whereby the same embraces the side faces of the end of the body portion of the heddle, each of said members having substantially parallel leg portions each having a recess therein open to the side, the recess of one leg portion opening to the side opposite that to which the recess of the other leg portion opens, and lip portions contiguous to said recesses adapted to overlap the sides of the supporting rod.

7. A heddle having its body portion made of a thin flat strip of metal or wire, members welded to said body portion at the ends thereof for mounting the heddle on the supporting rods, each of said members being made of a single piece of thin flat metal centrally apertured and bent whereby the same embraces the side faces of the end of the body portion of the heddle, said members having substantially parallel leg portions each having a recess therein open to the side, the recess of one leg portion opening to the side opposite that to which the recess of the other leg portion opens, and lip portions contiguous to said recesses adapted to overlap the sides of the supporting rod.

8. A heddle having its body portion made of a thin flat strip of metal or wire, members welded to said body portion at the ends thereof for mounting the heddle on the supporting rods, each of said members being made of a single piece of thin flat metal centrally apertured and bent whereby the same embraces the side faces of the end of the body portion of the heddle, said members having substantially parallel leg portions each having a recess therein open to the side, the recess of one leg portion opening to the side opposite that to which the recess of the other leg portion opens, and lip portions contiguous to said recesses adapted to overlap the sides of the supporting rod, the outer end of at least one of the leg portions of each end member being bent out of the main plane thereof to facilitate the engagement of the end member with the supporting rod.

9. A heddle having its body portion made of a thin flat strip of metal or wire, members secured to said body portion at the ends thereof for mounting the heddle on the sup-

porting rods, said members being made of thin flat metal and comprising leg portions disposed in separate parallel planes, each of said leg portions having a recess therein open to the side, the recess of one leg portion opening to the side opposite to which the recess of the other leg portion opens, the outer end of at least one of the leg portions of each end member being bent out of the main plane thereof to facilitate the engagement of the end member with the supporting rod.

In testimony whereof, I have hereunto signed my name.

15 JOHN JACOB KAUFMANN.
